MATCH TIP CIGARETTE

Dominic Alfred Raffa, Brooklyn, N. Y.

Application March 10, 1945, Serial No. 582,001

5 Claims. (131-7)

1

This invention relates to new and useful improvements in cigarettes, and more particularly to a match tip cigarette which may be lighted without requiring matches. The invention also may be applied to cigars, and other smoking devices.

More specifically, the invention proposes the introduction of a cigarette or the like having a match tip mounted in and projecting from one end by which it may be lighted when desired. The dominating feature of this construction resides in the fact that no matches are needed with the new cigarette or the like and it is not necessary to supply smokers with the usual book of matches, or boxes of matches. Moreover, the annoyance of having to look for a match is eliminated.

The invention contemplates providing the package of cigarettes with a striker area so that when one of the match tip cigarettes is removed, it may be lighted by rubbing it in the usual way, across the striker area.

Another object of the invention resides in the fact that the construction and design of the match tip cigarettes is such that they may be manufactured and sold at a low cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of a package of match tip cigarettes constructed in accordance with this invention.

Fig. 2 is a fragmentary side elevational view of the match tip end of one of the cigarettes shown in Fig. 1.

Fig. 3 is a fragmentary enlarged sectional view taken on the line 3—3 of Fig. 2.

In Fig. 1 there is shown a package of cigarettes 10 provided with a match striker element 11 mounted on one end, or any portion thereof. This package 10 includes a plurality of cigarettes 12, each of which is provided with a match tip 14 mounted in and projecting from one end.

The match tip 14 comprises the usual ignitable material found upon the ends of matches. The match tip 14 is embedded into the tobacco in the end of the cigarette, to be in position while the cigarette is lighted. A support member 15 is mounted through the end portion of the cigarette, and is engaged beneath the bottom of

2

the match tip 14 for assisting in holding the match tip in position, in conjunction with the holding action of the tobacco. The member 15 has its ends 16 engaging through the jacket of the cigarette, by which it is supported.

A reinforcement band 17 of paper, or other reinforcement material, is mounted around the end of the cigarette 12 and forms an auxiliary support for the support wire 15. The match tip 14 is also provided with an eyelet 18 through which the support wire 15 passes. The match tip 14 may be formed on the eyelet 18, by the usual dipping process. With this construction, the match tip 14 will be held secure, particularly when the cigarette is mis-handled and some tobacco falls out of the end.

The operation of the match tip cigarette may be understood from the following:

The cigarettes are packaged in the usual way, 20 in packages such as illustrated in Fig. 1. There are usually 20 cigarettes to each package. The bottom corner of the wrapper may be torn, to expose some of the cigarettes, which may be removed. Instead of requiring a match to light the cigarette, it is merely necessary to strike the end of the cigarette across the striker 11 so that the match tip 14 engages the striker 11 and bursts out into flame. This flame is sufficient to light the end of the cigarette.

While I have illustrated and described the preferred embodiment of my invention, it is to be understood that I do not limit myself to the precise construction herein disclosed and the right is reserved to all changes and modifications 35 coming within the scope of the invention as defined in the appended claims.

Having thus described my invention, what I claim as new, and desire to secure by United States Letters Patent is:

40 1. A cigarette having an outer casing enclosing the usual tobacco filler, comprising a reinforcement member encircling the outer casing of the cigarette at one end while leaving the end area completely exposed, a match tip embedded partially into the exposed end of the cigarette and formed with an eyelet in its embedded portion, and an anchorage member for the match tip passing laterally through the tobacco filler at the said end of the cigarette and having its intermediate area passing through the eyelet and its ends projected through the outer casing at the sides of the cigarette and anchored in the reinforcement member.

45 2. A cigarette having an outer casing enclosing the usual tobacco filler, comprising a rein-

forcement member encircling the outer casing of the cigarette at one end while leaving the end area completely exposed, a match tip embedded partially into the exposed end of the cigarette and formed with an eyelet in its embedded portion, and an anchorage member for the match tip passing laterally through the tobacco filler at the said end of the cigarette and having its intermediate area passing through the eyelet and its ends projected through the outer casing at the sides of the cigarette and anchored in the reinforcement member, said reinforcement member comprising a band of reinforcing paper secured in position about the cigarette.

3. A cigarette having an outer casing enclosing the usual tobacco filler, comprising a reinforcement member encircling the outer casing of the cigarette at one end while leaving the end area completely exposed, a match tip embedded partially into the exposed end of the cigarette and formed with an eyelet in its embedded portion, and an anchorage member for the match tip passing laterally through the tobacco filler at the said end of the cigarette and having its intermediate area passing through the eyelet and its ends projected through the outer casing at the sides of the cigarette and anchored in the reinforcement member, said reinforcement member comprising a straight piece of wire.

4. A cigarette having an outer casing enclosing the usual tobacco filler, comprising a reinforcing band of paper encircling the outer casing of the cigarette at one end while leaving the end area completely exposed, an ignitable member embedded partially into the exposed end of the cigarette, and a straight piece of wire passing laterally through the tobacco filler at the said end of the cigarette and having its ends passing

through the outer casing at the sides of the cigarette and anchored in the reinforcing band, said ignitable member being attached to an intermediate portion of the wire.

5. A cigarette having an outer casing enclosing the usual tobacco filler, comprising a reinforcing band of paper encircling the outer casing of the cigarette at one end while leaving the end area completely exposed, an ignitable member embedded partially into the exposed end of the cigarette, and a straight piece of wire passing laterally through the tobacco filler at the said end of the cigarette and having its ends passing through the outer casing at the sides of the cigarette and anchored in the reinforcing band, said ignitable member being attached to an intermediate portion of the wire, said ignitable member comprising a match tip formed with an eyelet in its embedded portion through which an intermediate portion of the wire extends for anchoring the match tip.
